UNITED STATES PATENT OFFICE

ROY A. BOLEY, OF KENMORE, NEW YORK, ASSIGNOR TO OXWELD ACETYLENE COMPANY, A CORPORATION OF WEST VIRGINIA

ACETYLENE GENERATOR

Application filed September 12, 1928. Serial No. 305,536.

My invention relates to acetylene generators, particularly of the portable type, and has for one of its objects the provision of means for avoiding the production in a generator of excess pressures of gas, of an explosion, and similar injuries in the event of displacement of the generator from the normal position, as by overturning, etc.

The use of portable acetylene generators has heretofore been limited by the difficulty of avoiding hazard from excess gas production, and like difficulties, which may occur in the event that the generator is overturned and the water therein allowed to come into contact with the mass of stored calcium carbide, and from the fragile character and undependable nature of the structures previously made. Accordingly, for service in the field, such as blowpipe welding and similar utilization of acetylene, it has become customary to employ bottled acetylene, instead of following the simpler and more convenient method of generating the acetylene directly from carbide, in order to avoid such industrial hazard from the previous designs of generators.

My invention provides an acetylene generator having safety means for removing such hazard. It provides a container for water and sludge, and a chamber for the storage of carbide, with means for feeding from the stored carbide to the water. The chamber is desirably fluid tight at all points except the feed opening, and its parts are so proportioned and the feed opening so located that in the event the generator is overturned, only negligible and harmless quantities of water can make their way into the mass of stored carbide, and accordingly no danger of explosion or other hazard occurs.

Other objects and details of my invention will be apparent from the following description when read in connection with the accompanying drawings, wherein;

Figure 1 is a view in vertical section of the device of my invention,

Figure 2 is an exterior view showing the filling means, and,

Figures 3, 4, and 5 are diagrammatic views

showing the relationship of the parts under various conditions of displacement.

In the device of my invention, I provide a container 1 which is desirably cylindrical in shape. The container is equipped with a stirring means 2 having a handle 3, a drain 4, and filling means including a funnel 5 and piping 6. The container is provided with a cover 7 adapted to be tightly attached thereto. Upon the under side of the cover 7 is mounted a carbide chamber 8 having a feed cone device 9, actuated by a spring motor and governor 11.

The filling funnel 5 is so positioned as to limit the water level within the container 1 to a point well below the middle of the height by acting as an overflow, in the event that an excess amount of water is poured in. The water level, as located by the funnel, is held at such a point that the total volume of water which can be put in, is less than the volume of that portion of the container lying below the edge 12 of the bottom opening in the chamber 8 when the cylinder 1 is tipped to bring its axis into a horizontal position. Under such conditions an overturning of the container does not result in the water level rising to such a point with respect to the feed cone 9 and edge 12 of the cooperating opening in the chamber 8 that water can flow into the stored carbide within the container 8. The container is fluid tight at all other points, and accordingly no leakage of water occurs into it.

If desired, the chamber 8 may be made of such length and the funnel 5 positioned at such a point that the total amount of water which can be put into the container is less than the volume of the annular space around the chamber 8, between the edge 12 of the bottom opening, and the inner surface of the cover 7. This positions the feed opening from the carbide chamber 8 adjacent the volumetric mid-point of the container. This construction permits the generator not only to be overturned upon the side, but also to be completely reversed, to stand on the cover 7, as might occur if the generator fell over the edge of an excavation, without danger of water entering the carbide chamber.

By this means I am enabled to construct an acetylene generator which may be completely overturned during the course of usage, while containing charges of both carbide and water, without danger of the generation of excess quantities or excess pressures of acetylene gas therein, or of mechanical injury to its parts.

While I have shown but a single embodiment of the device of my invention it is adapted to still other modifications therefrom without departure of the spirit thereof and it is desired therefore that only such limitations shall be imposed thereon as are required by the prior art or indicated by the appended claims.

I claim as my invention:

1. An acetylene generator comprising a container having a top, a carbide chamber sealed centrally on the top so as to project a substantial distance into the container and provide a space between the exterior of the wall of the carbide chamber and the interior of the wall of the container, means for feeding carbide into the container through an opening in the chamber, and a water overflow on the container situated so as to limit the charge of water to a volume no greater than the space around the carbide chamber between the top of the container and said opening.

2. An acetylene generator comprising a container having a top, a carbide chamber sealed on the top so as to project a substantial distance into the container and provide a space between the exterior of the wall of the carbide chamber and the interior of the wall of the container, means for feeding carbide into the container through an opening in the carbide chamber, means for limiting a charge of water so that its level will be a substantial distance below said opening when the container is in a normal upright position and the volume of water will be no greater than the space around the carbide chamber between the top of the container and said opening, the height and diameter of the container being proportioned to give a space between the water level and said opening which is no less than that occupied by the limited volume of water when the container is tilted in any position.

In testimony whereof, I affix my signature.
ROY A. BOLEY.
